UNITED STATES PATENT OFFICE.

PAUL LUX, OF WATERBURY, CONNECTICUT, ASSIGNOR TO THE WATERBURY CLOCK CO.,
OF WATERBURY, CONNECTICUT, A CORPORATION.

ALARM-CLOCK.

990,573.

Specification of Letters Patent. Patented Apr. 25, 1911.

Application filed October 10, 1910. Serial No. 586,264.

To all whom it may concern:

Be it known that I, PAUL LUX, a citizen of the United States, residing at Waterbury, in the county of New Haven and State of Connecticut, have invented a new and useful Improvement in Alarm-Clocks; and I do hereby declare the following, when taken in connection with the accompanying drawings and the letters of reference marked thereon, to be a full, clear, and exact description of the same, and which said drawings constitute part of this specification, and represent, in—

Figure 1 a view in front elevation of a clock constructed in accordance with my invention with the upper portion of the dial broken away to show the clock-movement with particular reference to the switch for converting the clock from a long alarm to an intermittent alarm and vice versa, and to the switch for cutting out the alarm altogether. Fig. 2 a broken view of the clock in vertical central section, showing the clock adjusted for sounding a long alarm, and also showing the alarm as shut off. Fig. 3 a view of the clock partly in plan, and partly in horizontal section. Fig. 4 a detached view in side elevation of the case-body. Fig. 5 a view of the clock in side elevation with its ring-head and ring broken away. Fig. 6 a detached broken view in vertical central section through the case back and bell, with particular reference to showing the posts mounted in the rear plate of the clock-movement and extending through the case-back for the support of the bell and the brace or prop by means of which the completed clock is supported in an upright position.

My invention relates to an improvement in that class of alarm-clocks furnished with circular sheet-metal cases and concentric bells, the object being to produce a compact, convenient and reliable clock constructed with particular reference to the employment of large heavy bells without unduly thickening the clocks from front to rear, and to providing a slightly and convenient position and arrangement for the two switches by means of which the alarm is changed from a long to an intermittent alarm and vice versa, and by which the alarm is entirely cut off.

With these ends in view my invention consists in a clock having certain details of

construction and combinations of parts as will be hereinafter described and pointed out in the claims.

In carrying out my invention as herein shown, I produce from a single piece of sheet-metal a circular case-body characterized by a convex closed, crowning circumferential hollow enlargement or band 2 merging at its rear edge into a rearwardly projecting closed case-back 3 and at its forward edge into a concentric bezel-ring flange 4 which is narrower than the back 3 which, so to speak, is shallower than the crowning band 2 forming the main or characteristic feature of the case, and, as shown, twice as wide as the said back 3 is deep. The band 2 aforesaid is bead-like or crowning in form and larger in diameter than the case-back 3 or the flange 4 and receive the ring-head 5 and ring 6, as well as the legs 7. The said band 2 also receives the alarm-switch 8 and the cut-off switch 9 which, as shown, are symmetrically arranged on either side of the ring-head 5 and slide circumferentially in the plane of the case.

The closed rearwardly projecting case-back 3 is formed in its side wall with a lateral bell hammer opening 10 through which the hammer-head 11 on the hammer-wire 12 strikes the inner face of the forward edge of the deep flange 13 of a large heavy concentric bell 14 which, as shown, is attached by screws 15 on the opposite sides of but close to its center, to short posts 16 riveted in and close to the center of the rear movement-plate 17 of the clock. The bell 14 is made enough larger in diameter than the said case-back 3 to form an annular clearance space 18 as seen in Fig. 3. In this space 18 the hammer-head 11 vibrates in striking the edge of the bell. Under this construction I avoid passing the hammer-wire 12 rearward through an opening in the back of the case as is usually done, and therefore secure a more direct action of the hammer upon the bell and save space from front to rear. The forward edge of the flange 13 of the bell 14 just clears the rounded rear face of the crowning band 2.

The clock-movement itself may be of any approved construction and will not therefore be illustrated or described further than called for by the immediate purposes of this present description. Its pillars 19 are passed through the edges of the case-back 3

to which the movement is secured by nuts 20. Nuts 21 also screwed upon the rear ends of the pillars 19 secure the rear movement-plate 17 to the said pillars and form a space 22 between the rear movement-plate 17 and the back 3.

A bezel-ring 23 sleeved over the bezel-ring flange 4 and secured thereto by screws 24, holds the glass 25 against the outer edge of the dial-mat 26 which rests upon the dial 27 which in turn is secured to the dial-back 28 which is formed with rearwardly extending fingers 29 resting upon the front-plate 20 in the usual manner.

15 The switch-nobs 8 and 9 are formed with inwardly extending stems 30 and 31 passing through slightly bowed switch-plates 32, and also through friction springs 33, the said plates and springs respectively bearing upon 20 the outer and inner faces of the crowning-band 2 of the case-body, the said band being formed with slots 34 to permit the sliding movement of the knobs. The said plates 32 are provided with the wording (not shown) 25 necessary to indicate the functions of the respective knobs 8 and 9. The inner end of the stem 30 of the switch knob 8 engages with the upper end of an intermittent alarm-lever 35 hung upon an arbor 36 and provided 30 with a coiled-spring 37 which exerts a constant effort to hold the finger 38 formed upon the lower or inner end of the lever in operative relation to the intermittent alarm-cam 39 which is driven by the time-movement 35 of the clock in the ordinary manner, and which, at regular intervals, lifts the lever 35 for the intermittent sounding of the alarm when the switch 8 is moved upward to the limit of its sliding movement so that its 40 stem 30 clears the upper end of the lever 35 as shown in Fig. 1. The alarm-train having been released by the lifting of the lever 35 by the wheel 39, is intermittently stopped by the engagement of a tooth 40 on the lever 45 35, by a pin 41 carried by the alarm-escape wheel 42 which is engaged in the usual manner by a verge 43 mounted upon a verge-arbor 44 carrying the hammer-wire 12 aforesaid. The said arbor 44 also carries a bent 50 wire 45 commonly known as the "hammer tail." This wire 45 co-acts, in the usual manner, with a flat sheet metal alarm-cam-spring 46 which, when it is allowed to spring forward, releases the hammer-tail 45, and thus permits the vibration of the hammer. The extreme end of the wire 45 engages with the bent inner end of a stop-lever 47 hung upon an arbor 48 and having its upper end bent for engagement by the stem 31 of the 55 switch-knob 9. When the said knob 9 is at the limit of its upward sliding movement, as shown in Fig. 1, it has no effect upon the stop-lever 47. When, however, the knob 9 is moved from left to right, and therefore 60 downward into its operative position as

shown in Fig. 2, its stem 31 engages with the stop-lever 47 and throws the same against the hammer-tail 45 the vibration of which is thus prevented so that neither a long nor a short alarm may be sounded. By moving 70 the switch-knob 8 from right to left, and therefore downward, its stem 30 engages with the upper end of the lever 35 and throws the same into its retired position in which it is not operated upon by the cam-wheel 39 so that a long alarm will be sounded rather than an intermittent alarm. Other means than those shown might be employed for causing the switch-knobs 8 and 9 to act upon the movement so as to cut off the alarm 80 altogether, or to convert it from an intermittent to a long alarm, and vice versa, my invention consisting in particular, in this respect, in mounting the switch-knobs in the central band or crowning enlargement of the 85 case-body and arranging them so as to be moved circumferentially over the same in one direction or the other in the plane of the case.

As shown, the clock is supported by the 90 legs 7 aforesaid, and by means of a rearwardly extending sheet-metal prop or brace 49 held in place by the screws 15 employed to secure the bell 14 to the posts 16, as shown in Figs. 3 and 5. The bell 14 and the prop 49 are thus secured through the medium of the short posts 16 to the rear movement-plate 17, rather than to the central portion of the relatively light sheet-metal case-back 3. Fig. 5 also shows the knurled button 50 by means of which the alarm is set, and the knurled button 51 by means of which the hour and minute hands are set.

I claim:—

1. In an alarm clock, the combination 105 with a one-piece sheet-metal case-body comprising a crowning circumferential hollow band, a concentric rearwardly projecting closed case-back smaller in diameter and shallower than the said band and formed 110 with a lateral bell-hammer opening, and a bezel-ring flange projecting forwardly from the forward edge of the said band and smaller in diameter than the same; of a clock-movement located within the said case-body, secured to the case-back thereof and provided with a hammer located adjacent to the said bell-hammer opening, a bell encircling the said case-back and extending forwardly over the same, its forward edge 115 clearing the rounded rear portion of the said crowning band; and a bezel-ring secured to the said bezel-ring flange.

2. In an alarm clock, the combination 125 with a case-body having a closed back made integral with it, of a concentrically arranged bell encircling the said back of the said case-body, a clock-movement located within the said case-body and secured to the said case-back near the edges thereof, posts 130

- mounted in the rear movement-plate of the clock movement close to the center of the said plate and extending rearwardly therefrom through the central portion of the case-back and through the bell which they support, and a brace or prop secured to the projecting rear ends of the said posts for assisting in supporting the clock in an upright position.
- 10 3. In an alarm clock, the combination with a one-piece sheet-metal case-body having a crowning hollow circumferential band formed in its periphery and on the opposite sides of its apex with two switch-knob slots,
- 15 a concentric rearwardly projecting closed case-back smaller in diameter and shallower than the said band, and a bezel-ring flange extending forward from the forward edge of the said band and smaller in diameter
- 20 than the same; of an alarm-movement located within the said case-body, two switch-knobs respectively mounted in the said switch-knob slots and having circumferential sliding movement therein in the vertical
- 25 plane of the said crowning band; and means for connecting the said switch-knobs with parts of the alarm-movement.
4. In an alarm clock, the combination with a one-piece sheet-metal case-body having a crowning hollow circumferential band formed in its periphery with a switch-knob slot, of an alarm-movement located within the said case-body and provided with a hammer and a hammer-tail, a stop-lever mounted
- 30 upon the said movement, and a switch-knob mounted in the said switch-knob slot for circumferential movement therein in the plane of the said band and coacting with the outer end of the said stop-lever the inner end
- 35 of which coacts with the said hammer-tail.
5. In an alarm clock, the combination with a one-piece sheet-metal case-body having a crowning hollow circumferential band formed on opposite sides of its apex with
- 40 peripheral switch-knob slots, of a ring head applied to the apex of the said band be-
- tween the inner ends of the said slots, an alarm-movement located within the said case-body and provided with an intermittent-alarm lever and a stop-lever, and 50 switch-knobs respectively mounted in the said switch-knob slots for circumferential sliding movement therein in the plane of the clock and provided at their inner ends with stems respectively coacting with the outer 55 ends of the said intermittent-alarm lever and stop-lever.
6. In an alarm clock, the combination with a one-piece sheet-metal case-body having a crowning circumferential band formed in 60 its periphery and on the opposite sides of its apex with two switch-knob slots, of a ring-head applied to the apex of the said band between the inner ends of the said slots, a clock-movement located within the 65 said case-body and provided with an alarm mechanism including an alarm-cam, an alarm-cam spring, an alarm-hammer, an alarm-hammer tail and an intermittent alarm cam; a stop-lever pivotally mounted upon 70 the said clock-movement in position to have its lower end co-act with the said hammer tail, an intermittent alarm-lever also mounted upon the said clock movement and co-acting with the said intermittent alarm-cam, 75 and two switch-knobs respectively mounted in the said switch-knob slots and having circumferential sliding movement therein in the vertical plane of the said crowning band and respectively co-acting with the outer 80 ends of the said stop-lever and intermittent-alarm lever, the said hammer tail co-acting both with the alarm-cam spring and with the stop-lever.

In testimony whereof, I have signed this 85 specification in the presence of two subscribing witnesses.

PAUL LUX.
